UNITED STATES PATENT OFFICE.

ERNST F. H. ENNA, OF COPENHAGEN, DENMARK.

EYELET-SETTING MACHINE.

Application filed December 26, 1922. Serial No. 608,813.

To all whom it may concern:

Be it known that I, ERNST F. H. ENNA, a subject of the King of Denmark, residing at Copenhagen, Denmark, have invented 5 new and useful Improvements in Eyelet-Setting Machines, of which the following is a specification:

This invention relates generally to the parts or elements of an eyelet-setting machine which include the setting member and the elements which cooperate therewith in spreading and splitting the end of an eyelet barrel opposite the previously formed flange or head, and in clenching the prongs 15 into which the barrel end is split, to completely set the eyelet in the material by which it is carried.

The invention relates in particular to said elements, when organized to perform the 20 operation of blind eyeletting, the eyelet being inserted, in some instances, in the inner side of a group composed of a plurality of superimposed layers including an inner facing layer, a lining, and an outer layer constituting an exposed portion of a shoe upper.

In other instances the eyelet is inserted from the outer side of the group of layers. In each instance, the eyelet is clenched in and secured to layers at one side of the 30 group and concealed by the layer at the opposite side, without being engaged therewith.

An application for Letters Patent of the United States, filed by myself and Anton 35 Haahr, September 11, 1922, Ser. No. 587,297, discloses improved mechanism whereby the eyelets are clenched between the engaged layers and the concealing layer, without liability of entering, or in any way engaging the concealing layer, so that the latter is entirely separate from the eyelets. Said mechanism includes a setting member, having a setting shoulder adapted to cooperate with an anvil in partly spreading an 40 eyelet barrel inserted in adjacent layers, a hammer adapted to cooperate with the anvil and with the concealing layer in clenching the eyelet on one of said adjacent layers, and means for depressing said setting member 45 and hammer successively, so that the partial spreading of the eyelet precedes the clenching thereof, and the clenching is effected wholly at one side of the concealing layer. The hammer is adjustably connected with 50 the means whereby it is depressed, and is adjustable manually to initially set it at dif-

ferent distances above the setting shoulder, and cause it to conform to the thickness of the superimposed layers.

The object of the present invention is to 60 provide means for automatically adjusting the hammer, so that no manual adjustment of the same is required.

The invention is characterized by the improved means hereinafter described and 65 claimed, for attaining the above-mentioned object.

Of the accompanying drawings forming a part of this specification,—

Figure 1 shows partly in elevation, and 70 partly in section, parts of an eyelet-setting machine including the automatic means in which the present invention is embodied.

Figure 2 is a section on line 2—2 of Figure 1, and a plan view of parts below said line, other parts shown by Figure 1 on said line being omitted.

Figure 3 is a section on line 3—3 of Figure 1.

Figures 4, 5, 8 and 9 are fragmentary 80 views, illustrating different stages of the punching and setting operation.

Figures 6 and 7 are perspective views, showing respectively, the nipple and the 85 hammer hereinafter described.

The same reference characters indicate the same parts in all of the figures.

In the drawings, 12 represents the setting member which is, in this instance, a tubular punch, adapted to form coinciding 90 holes in a plurality of superimposed layers of material.

The setting member is enlarged above its lower end, to provide a circumferential downwardly facing setting shoulder 13, 95 adapted to split and spread one end of the barrel of an eyelet pressed against said shoulder, the eyelet having at its opposite end the usual previously formed flange or head.

The upper end portion of the setting member is externally screw-threaded, and engaged with a tapped socket, in a vertically reciprocating plunger 15, which is movable in a fixed guide 16, suitably supported on 105 the frame of an eyelet-setting machine of a well known type, such as the Glass machine, disclosed by Letters Patent of the United States, Nos. 686,928, dated November 19, 1901, or 673,815, dated May 7, 1901. The 110 setting-machine is equipped with the usual anvil 17, on which the head of the eyelet

rests, and with the usual positioning point 18, which catches and properly positions the eyelet upon the anvil, as the eyelet is fed from the reservoir through the chute or race-
5 way of the machine.

To the plunger 15 is fixed, as by nuts 19, a cross-head 20, having a recess 21, in its outer side, the upper and lower sides 22 of said recess forming horizontal guides in
10 which a block 23 is moved by any suitable means to vertically reciprocate the cross-head and plunger. As here shown, the block 23 is provided with a socket 24, in which may be loosely fitted a wrist-pin, to
15 which an orbital movement is imparted, in such manner as to cause the block to move both horizontally and vertically, the block sliding from end to end of the guides 22, and at the same time reciprocating the cross-head and plunger vertically.
20

Projecting from the inner side of the block 23 is a lug 26, which is movable in a horizontal slot 27, in the cross-head 20, and is provided with inclined or bevelled side
25 faces, preferably curved, as shown by dotted lines in Figure 1, and adapted to engage correspondingly bevelled end faces 28, on the upper end of a cylindrical slide or secondary plunger 29, which is vertically movable to a limited extent, in the bore of the
30 plunger 15, the latter, which may be called the primary plunger, being tubular above its lower end portion, to form a guide for said secondary plunger.
35

30 represents a ring or sleeve, which embraces and is slidable to a limited extent, on the reduced lower end portion 15^a of the primary plunger, and is normally held yieldingly, by means presently described, against
40 a shoulder 15^b at the upper end of said reduced portion. The ring 30 is provided with a pair of upwardly projecting arms 31, which are movable in vertical guiding slots 32, in opposite sides of the fixed guide 16.
45

To the upper ends of the arms is secured a transverse pin 33, closely fitted in a transverse orifice in the secondary plunger 29, and passing through vertical slots 34 in the primary plunger 15. A spring 35 interposed between the lower end of the secondary plunger, and an abutment 36, formed by the closed end of the bore of the primary plunger, normally holds the ring 30 yieldingly against the shoulder 15^b, and yieldingly supports the secondary plunger with its bevelled end faces 28 in the path of the block lug 26.
55

The ring 30 is provided at its lower end with a reduced externally threaded nipple
60 37, with which is engaged an annular hammer, composed of a base 38, internally threaded to engage the nipple 37, and a sleeve 39, surrounding a portion of the setting member 12, and provided with an in-
65 wardly projecting annular flange 40, which

constitutes the head of the hammer, and surrounds the setting member above the shoulder 13.

When the primary plunger 15 is raised, the setting member 12 is spaced from the anvil 17, the block 23 being at one end of its movement in the cross-head 20, so that the lug 26 is spaced from the end faces 28 of the secondary plunger. The movement of the block which depresses the cross-head and the primary plunger, causes said plunger and the secondary plunger 29 to move downward in unison, until the upper end of the barrel of an eyelet 44, whose head 44^a is supported by the anvil 17, is partially split and spread by the shoulder 13 of the setting member. When the setting member reaches this position, the lug 26 of the block 23 encounters one of the end faces 28, and in passing across the same, additionally depresses the secondary plunger 29, thereby depressing the hammer. The hammer in moving to its depressed position, acts through the layer 43, hereinafter described, to complete the

The foregoing description is reproduced from the specification of the above-mentioned joint application, the drawings of which show more in detail certain features above described, and other features not relating to the present invention. The said drawings show the nipple 37, and the hammer base 38, continuously connected by the screw threads with which they are provided, so that to adjust the hammer toward and from the setting shoulder 13, it is necessary to manually rotate the hammer.

In carrying out my invention I provide for the automatic adjustment of the hammer to the thickness of the superimposed layers, as next described. The hammer is adapted to be turned, or partially rotated about its center, by means preferably embodied in gear teeth 45^a, arranged in a segmental series on the base 38, and a rack 60, which is held in the path in which the setting member, the hammer, and the associated parts are given a work-feeding movement from punching position shown by Figures 1 and 4, over a bed 58, to a setting position over the anvil 17, as shown by Figure 5, this movement being caused by suitable means, well known in this art.

When the gear teeth 45^a are engaged with the rack by the feeding movement, the hammer is turned in one direction, and when the said movement is reversed to carry the setting member, and the associated parts, back to the position shown by Figure 1, the hammer is turned in the opposite direction.

A separable connection is provided between the hammer and the secondary plunger, whereby, when the hammer is turned by the feeding movement, it is positively connected with the secondary plunger, and when the hammer is turned by the return movement, it is released, and permitted to bear loosely by its own weight on the concealing layer 43, so that it adjusts itself to the upper surface of said layer. Said connection is preferably provided by interrupting the external thread of the nipple 37, so that the nipple has longitudinal threaded portions 52, alternating with unthreaded portions 53, and by similarly interrupting the internal thread in the nipple-receiving socket in the hammer base 38, so that the socket has longitudinal threaded portions 50, alternating with unthreaded portions 51. When the hammer is in the position shown by Figures 1 and 4, the portions 51 coincide with the threaded portions 52, so that the hammer is loose. When the hammer is over the anvil, as shown by Figure 5, the threaded portions 50 engage the threaded portions 52, so that the hammer is positively connected with the nipple 37, and with the secondary plunger, and is caused by the descent of said plunger to cooperate with the concealing layer 43, in clenching the eyelet. To support the ham-

mer against an excessive downward movement when it is loose, I provide means loosely connecting the hammer base with the fixed guide 16, at points above the hammer, said means being preferably embodied in vertical rods 54, fixed at their lower ends to the hammer base 38, and having hooks 54^a, at their upper ends, loosely bestriding and slidable on arcuate resilient guide rods 55. Said rods are fixed to studs 57, which are fixed to the guide 16. The rods and hooks limit the downward movement of the hammer when the latter is loose, and permit any required upward movement of the hammer, and the described turning movements thereof.

The rack 60 may be fixed to the usual presser-foot 59, and said foot may be movably secured in place by an arm 59^b, adapted to swing on a fixed stud 59^a, so that the presser-foot and the rack may be displaced by swinging the arm on the stud.

I claim:

1. An eyelet-setting machine, comprising a setting member adapted to cooperate with an anvil in partly spreading an eyelet barrel inserted in adjacent layers, a hammer adapted to cooperate with the anvil and with a concealing layer in clenching the eyelet on one of said adjacent layers, means for depressing said setting member and hammer successively so that the partial spreading of the eyelet precedes the clenching thereof and the clenching is effected wholly at one side of the concealing layer, 90 said means including a reciprocating plunger, a separable connection between the hammer and the said plunger, and means for alternately releasing the hammer from and positively connecting it with the plunger. 95

2. An eyelet-setting machine, comprising a setting member adapted to cooperate with an anvil in partly spreading an eyelet barrel inserted in adjacent layers, a hammer adapted to cooperate with the anvil and with a concealing layer in clenching the eyelet on one of said adjacent layers, means for depressing said setting member and hammer successively so that the partial spreading of the eyelet precedes the clenching thereof and the clenching thereof is effected wholly at one side of the concealing layer, said means including a reciprocating plunger, a separable connection between the hammer and the said plunger, means for alternately releasing the hammer from and positively connecting it with the plunger, and means for loosely supporting the hammer when released from said plunger. 115

3. An eyelet-setting machine comprising, 125 in combination, a primary plunger, a punching and setting member fixed to said plunger and adapted to cooperate with an anvil in partly spreading an eyelet barrel inserted in adjacent layers, a secondary plunger mov- 130

able with and independently of the primary plunger, a hammer adapted to be partially rotated and formed to cooperate with the anvil and with a concealing layer in clenching the eyelet on one of said adjacent layers, means for depressing the primary and the secondary plunger successively, hammer-rotating means adapted to turn the hammer in opposite directions, separable connections between the hammer and the secondary plunger operable by a partial rotation of the hammer in one direction to positively connect the hammer with the plunger and by a partial rotation in the opposite direction to release the hammer from the plunger and render the hammer self-adjusting, and means for loosely supporting the hammer when released, so constructed as to permit it to rest loosely on the concealing layer, the hammer being depressed by the secondary plunger while it is positively connected with the said plunger, so that the clenching of the eyelet follows the partial spreading thereof, and is effected wholly at one side of the concealing layer.

4. An eyelet-setting machine substantially as specified by claim 3, the said hammer-

rotating means being embodied in gear teeth on the hammer base, and a rack adapted to engage said teeth and turn the hammer in opposite directions.

5. An eyelet-setting machine substantially as specified by claim 3, the said separable connections being embodied in an externally screw-threaded nipple movable in unison with the secondary plunger having alternating threaded and unthreaded portions, and an internally threaded socket formed in the hammer base, having alternating threaded and unthreaded portions, the threaded portions of the socket being engageable with, and separable from, the threaded portions of the nipple, by turning movements of the hammer.

6. An eyelet-setting machine substantially as specified by claim 3, said hammer-supporting means being embodied in hooked rods fixed to and projecting above the hammer base, and fixed arcuate guides above the hammer on which said rods are slideable.

In testimony whereof I have affixed my signature.

ERNST F. H. ENNA.
